WHEEL COVER

Bernard Plotkin, Los Angeles, Calif., assignor to
Wire Wheel Division, Calnevar Company, Los
Angeles, Calif., a corporation of California

Application December 23, 1952, Serial No. 22,855

Term of patent 14 years

(Cl. D14—30)

To all whom it may concern:

Be it known that I, Bernard Plotkin, a citizen of the United States, residing at Los Angeles, in the county of Los Angeles and State of California, have invented a new, original, and ornamental Design for a Wheel Cover, of which the following is a specification, reference being had to the accompanying drawing, forming part thereof.

Fig. 1 is a front view of a wheel cover, showing my new design; and

Fig. 2 is a cross-section taken along the line 2—2 of Fig. 1.

The dotted lines on the drawing are for illustrative purposes only.

I claim:

The ornamental design for a wheel cover, substantially as shown and described.

BERNARD PLOTKIN.
